UNITED STATES PATENT OFFICE.

JULIUS BROMBACHER, OF LOS ANGELES, CALIFORNIA.

PILOT-LIGHT BURNER.

1,423,750.

Specification of Letters Patent. Patented July 25, 1922.

Application filed November 19, 1921. Serial No. 516,460.

To all whom it may concern:

Be it known that I, JULIUS BROMBACHER, a citizen of the United States, residing at Los Angeles, county of Los Angeles, and State of California, have invented a certain new and useful Pilot-Light Burner, of which the following is a specification.

This invention relates to a gas burner and has especial reference to a pilot light for use 10 in connection particularly with water heaters having a thermostatic control.

One of the objects of this invention is to provide a cheap and easily constructed gas burning appliance in which the flame used 15 in a pilot light is prevented from being extinguished by winds or sudden currents of air. This and other objects is accomplished by the device shown in preferred form in the drawing, in which,

20 Fig. 1 is a perspective view.

Fig. 2 is a vertical section.

Fig. 3 is a plan view.

Fig. 4 is a plan view of a modified form 25 of gas divider, and

Fig. 5 is an elevation of another modified form of gas divider.

The invention consists of a pipe 1, arranged to be connected with a gas supply pipe and having any common means therein 30 for controlling the quantity of gas necessary for a pilot flame.

Near the top, the pipe 1 is provided with a shoulder 2, forming a seat for a gas dividing means 3, shaped and constructed to fit 35 snugly and loosely in the end of the pipe 1 and to provide passageways for the gas. For this purpose, the gas dividing means 40 may be made of a square bar of any suitable material, preferably soap-stone, which is fitted into the end of a round stand pipe 1, the spaces between the plane surfaces of the pipe forming passageways 4 for the gas, which, when burning, encircles the bar. The

flame is thereby insured against extinguishment by drafts and air currents through at 45 least two divisions or surfaces of the bar, which deflect the currents of air from opposite divisions or surfaces.

In Fig. 4, I have illustrated a slightly changed form of bar or gas divider. It consists of a round bar 5, arranged to fit snugly 50 in the end of the pipe 1, and provided with longitudinal grooves 6, forming substantially pockets in which the flame burns.

In Fig. 5 another modified form is shown. 55 It consists of a bar 7, either round or square, provided with grooves 8 which extend from one end to approximately the middle of the bar, which is inserted and held in the end of the pipe 1, in such manner that but part of 60 the grooves 8 thereof extend beyond the end of the pipe 1.

What I claim, is;

1. A pilot light burner comprising a gas supply pipe and a bar in the end of said 65 pipe formed to provide passageways for the gas.

2. A pilot light burner comprising a gas supply pipe and a bar in the end of said pipe co-operating with said pipe to form passageways for the gas. 70

3. A pilot light burner comprising a gas supply pipe and a bar fitting in the end of said pipe and providing passageways for the gas. 75

4. A pilot light burner comprising a gas supply pipe and a square bar of soap-stone fitting in the end of and extending beyond said pipe.

5. A pilot light burner comprising a gas 80 supply pipe having an internal shoulder, and a square bar loosely resting on the shoulder of, and extending beyond the end of, said pipe.

In testimony whereof I have set my hand. 85

JULIUS BROMBACHER.
